VARIABLE STROKE ROTARY WELL JAR

Edgar W. Bagnell and Wilbur F. Bettis, Glendale, Calif., assignors, by mesne assignments, to Johnston Testers, Inc., Houston, Tex., a corporation of Delaware

Application April 16, 1948, Serial No. 21,540

17 Claims. (Cl. 255—27)

1

This invention relates to well drilling equipment, and particularly pertains to a variable blow rotary well jar.

In well drilling operations it is often necessary to withdraw a section of drill string from a well bore after the section has become accidentally detached from the supporting string either by separation at a point or by a twist-off. The operation of recovering the detached member is commonly known as a "fishing" operation. In some instances the detached length of drill pipe is lodged in the well in such a manner as to require an enormous amount of force to dislodge it so that it can be withdrawn from the well bore. This operation is performed by a well jar. These jars for the most part have been connected to a fishing tool which engaged the detached part or "fish," and which were designed so that when a determined tension strain was imposed on the well jar by a supporting member the jar would release suddenly and its parts would have relative movement to each other, after which a violent impact is created tending to jar the fish loose from its position in the well bore. This type of jar requires that an intermittent operation must be performed in order to set the jar, tension it, and release it. It is desirable to provide a jar which is continuous in operation and which will set up a succession of jarring blows as the supporting drill string rotates. Heretofore jars of this type have been made but they have created only a relatively small impact blow which was constant, and which could not be varied in magnitude to meet the problem presented. It is the principal object of the present invention, therefore, to provide a rotary well jar including a hammer and anvil, and means whereby a desired tension strain may be set up and suddenly released to impart a jarring blow to the fish, and in which the magnitude of the blow may be varied adjustably.

The present invention contemplates the provision of a rotary well jar including upper and lower loosely coupled elements, one carrying a hammer and the other an anvil, and which elements are equipped with rotary clutch mechanism, the parts of which are designed to build up tension strain of a desired magnitude and to suddenly release this force so that it may be expended in impact between the hammer and the anvil.

The invention is illustrated by way of example in the accompanying drawings in which:

Figure 1 is a view in elevation showing the well jar as associated with a suspending string of pipe and a fishing tool.

Fig. 2 is an enlarged fragmentary section through the upper portion of the well jar as indicated on the line 2—2 of Fig. 1 and shows the upper portions of the jar in contracted position.

2

Fig. 3 is an enlarged fragmentary view in central longitudinal section as seen on the line 3—3 of Fig. 1 and shows the locking structure in its contracted position.

Fig. 4 is an enlarged fragmentary view in longitudinal section as seen on the line 4—4 of Fig. 1 and shows the jarring mechanism with the parts in their contracted positions.

Fig. 5 is an enlarged fragmentary view in longitudinal section as seen on the line 5—5 of Fig. 1 and shows the hammer and anvil structure in their contracted position.

Fig. 6 is a fragmentary view in central longitudinal section showing the parts previously disclosed in Fig. 2 in their extended positions.

Fig. 7 is an enlarged fragmentary view showing the parts previously disclosed in Fig. 3 in their extended positions.

Fig. 8 is an enlarged fragmentary view showing the parts of the jarring mechanism previously shown in Fig. 4 when the jar is in its extended position.

Fig. 9 is an enlarged fragmentary view showing the parts of the hammer and anvil structure previously disclosed in Fig. 5 but with the parts in their extended positions.

Fig. 10 is a view in longitudinal section and elevation showing the split nuts of the jarring mechanism and a portion of the threaded mandrel for actuating the same.

Fig. 11 is a view in transverse section through the lock structure as seen on the line 11—11 of Fig. 3.

Fig. 12 is a view in transverse section through the lock structure as seen on the line 12—12 of Fig. 7 and shows the engaging position of the splined portion thereof.

Fig. 13 is a view in transverse section through the jarring mechanism as seen on the line 13—13 of Fig. 4 and shows the relation of the split nut segments to the mandrel.

Fig. 14 is a view in transverse section as seen on the line 14—14 of Fig. 4 and shows the means whereby the split nuts are disposed in driving relation to the mandrel.

Fig. 15 is a view in transverse section as seen on the line 15—15 of Fig. 8 and shows the split nut structure.

Fig. 16 is a diagrammatic view showing the developed surface of the locking head with the parts in locked position, as indicated in Fig. 3 of the drawing.

Fig. 17 is a diagrammatic view similar to Fig. 16 and showing the locking head rotated preparatory to release.

Fig. 18 is a diagrammatic view similar to Fig. 16 showing the locking head released, thus placing the tool in condition for jarring operations.

Referring more particularly to the drawings, 69 10 indicates a fragmentary portion of a drill

string by which a well jar is supported. This member is formed with a pin 11 which is threaded into a box portion 12 of a coupling member 13. The lower end of the coupling member 13 is formed with a central cylindrical threaded bore 14. At a point between the box portion 12 and the threaded bore 14 an internal shoulder 15 is formed having a central opening 16 through it. An upper drive mandrel 17 is provided and has an upper end of reduced diameter, as indicated at 18, which is threaded into the bore 14. A shoulder 19 is formed on the mandrel 17 and abuts against the end face of the coupling 13. The lower end of the mandrel 17 is formed with a length 20 of enlarged diameter. Within this portion a bore 21 is formed. This bore is threaded at 22. Directly above the bore 21 is a bore 23 of reduced diameter. This bore extends for a distance sufficient to provide a suitable bearing surface for a purpose to be hereinafter described. Above the bore 23 is a counterbore 24. The counterbore 24 extends to the top of the drive mandrel 17 and is threaded at 25. A stuffing gland 26 is threaded into the counterbore and acts against suitable packing 27. A central mandrel 28 extends through the drive mandrel 17 and is of a diameter substantially agreeing with the bore 23 in the drive mandrel. The upper end of the central mandrel extends through the opening 16 in the coupling 13 and to a height above the shoulder 15 when the parts are locked in contracted position as shown in Figs. 2 to 5. This mandrel has a circulating passageway 29 through it. The lower end of the central mandrel 28 has an enlarged portion 28' which is disposed within the enlarged counterbore portion 21 of the drive mandrel. A threaded pin 30 is formed at the lower end of the central mandrel 28 and extends into a threaded bore 30' of a splined central mandrel head 31. This head is formed with a plurality of splines 32 extending longitudinally and arranged around its circumference. The splined portion occurs within a counterbore 33 of a drive mandrel extension 34. A threaded pin 35 is formed at the lower end of the splined head 31. This pin extends into a threaded bore 36 of a tubular central mandrel extension 37. The lower end of the drive mandrel extension 34 is formed with a threaded counterbore 38 which receives the upper threaded end of a locking head 39. The locking head 39 is thus rigidly secured to the drive mandrel extension 34 and moves with it. This head is formed with a central bore 40 which receives the tubular central mandrel extension 37 and upon which the head 39 reciprocates. The locking head 39 is formed at its upper end with a series of inwardly extending splines 41 and intermediate keyways 42 formed in the wall of the upper portion of the bore 40. Thus, when the locking head 39 is in its uppermost position splines 32 of the head 31 will be received within keyways 42 and the head 39 will be keyed to rotate with the head 31, and when it is in its lowered position it will be freely rotatable with relation to the tubular central mandrel extension 37. As shown diagrammatically in Figs. 16 to 18 of the drawings, it will be seen that the outer circumference of the locking head 39 is formed with an upper continuous cylindrical portion 43 and a pair of diametrically opposite arcuate segments 44. The cylindrical portion 43 provides a continuous shoulder 45 around the locking head, which shoulder is spaced a predetermined distance from the upper faces 46 of the arcuate segments 44.

Midway the length of each of the faces 46 of the arcuate segments and extending between these faces and the shoulder 45 are lugs 47. These lugs substantially span the space between the shoulder 45 and the faces 46 for a purpose to be hereinafter described.

The locking head 39 is disposed within a counterbore 48 formed in the upper end of a lock housing 49. The lock housing 49 has a central cylindrical bore 50 through which the tubular mandrel extension 37 extends. The upper end of the lock housing counterbore 48 receives the lower end of the drive mandrel extension 34. The outer circumference of the upper end of the lock housing 49 is externally threaded at 50' and extends into a threaded bore 51 formed in the lower end of a tubular lock housing top 52 which encloses the upper drive mandrel 17 and may reciprocate with relation thereto. The upper drive mandrel 17 is formed with a reduced diameter section 53 which terminates in a shoulder 54. This provides a fluid space 55 between the upper drive mandrel 17 and the wall of the lock housing top 52. Vent openings 56 extend through this wall to prevent fluid lock of the relative moving parts. This will insure free relative longitudinal movement between the locking head 39 and the lock housing 49 when required.

At the time the well jar is run into the well the locking head 39 and the lock housing 49 are held against relative longitudinal movement. This is accomplished by providing arcuate lock lugs 57 which extend inwardly from diametrically opposite sides of the counterbore 48 within the lock housing 49. These lugs are spaced in a plane longitudinally of the locking head 39 which will normally position them between the shoulder 45 and the faces 46. The vertical width of the lugs is substantially the distance between the shoulder 45 and the faces 46 so that relative rotation between the locking head and the lock housing will permit the lugs to slide between the faces and thus prevent relative longitudinal movement between the locking head 39 and the lock housing 49 while in this interlocked position. The end faces of the lugs 57 are radial and will abut against the radial side faces of the intermediate lugs 47 carried by the locking head 39. The construction and arrangement of these members is particularly disclosed in Fig. 11 of the drawing where the arcuate lugs 57 are shown as being disposed in locking position between the shoulder 45 and the faces 46 and abutting against the radial faces of the intermediate lugs 47. This position is also shown in the diagrammatic Fig. 16.

The bore 50 within the lock housing 49 is formed with a counterbore 58 which occurs beneath the counterbore 48. The counterbore 58 receives packing 59 and a stuffing gland 60 which is threaded into the upper end of the bore to create a fluid seal between the central mandrel extension 37 and the lock housing 49. At the lower end of the bore 50 within the lock housing 49 is a counterbore 61 which receives a helical engaging spring 62. This spring circumscribes the central mandrel extension 37 and is engaged at its lower end by a retaining member 63 which has a cylindrical portion fitting within the counterbore 61 and an inturned end flange 64 against which the lower end of the spring 62 rests. Longitudinal slots 65 in the cylindrical portion of the member 63 receive retaining pins 66 which permit the retaining member 63 to move upwardly while the spring is being compressed

and will limit the amount of expansion of the spring. The lower end of the lock housing 49 is externally threaded at 67 and extends into a threaded bore 68 formed in the end of a drive housing 69. The drive housing is cylindrical and tubular and has a central bore carrying a continuous thread 70. The thread 70 is here shown as an acme thread of coarse pitch. This thread produces the motion for a jarring stroke of the tool as will be hereinafter described. Before explaining the jarring structure it is desirable to describe the other elements making up the tool and its connection with the object to be jarred.

At the lower end of the drive housing 69 is a threaded bore 71 which receives a threaded pin section 72 of an anvil sub 73. The sub 73 is a cylindrical member internally threaded at its lower end as indicated at 74. The thread 74 receives a pin portion 75 of a bottom sub 76. The bottom sub is formed with an externally threaded pin 77 which may be attached to any desired type of fishing tool. The anvil sub 73 is formed intermediate its ends with a smooth cylindrical bore 78. The upper end of the anvil sub 73 is formed with a bore of reduced diameter, as indicated at 79. An anvil 80 is thus formed at the upper end of the cylindrical bore 78 and at the beginning of the lower end of the reduced bore 79. Extending through the anvil sub 73 and the bottom sub 76 is a hammer mandrel 81. This mandrel is free to slide longitudinally of the bores 78 and 79 in the anvil sub 73 and a central bore 82 in the bottom sub 76. The central bore 82 is provided with a stuffing gland 83 so that the joint between the bottom sub 76 and the lower portion of the hammer mandrel 81 will be fluid-tight. Formed around the circumference of the hammer mandrel 81 and at a point midway its length is a hammer 84. This hammer is of a diameter to have a sliding fit within the bore 78 of the anvil sub and is formed with a hammer face 85 which is opposed to the anvil face 80 so that the hammer and anvil may have impact when the well jar is in operation. A face 86 is formed at the lower end of the hammer 84 and is opposed to an end face 87 on the bottom sub 76. An intermediate space 88 occurs between the face 86 and 87. This space is substantially fluid-tight and is free of liquid. At the upper end of the bore 79 within the anvil sub is a counterbore 72' at the bottom of which packing is mounted as indicated at 89. This is for the purpose of making a fluid-tight connection between the bore 79 and the circumference of the hammer mandrel 81. Thus the space 90 occurring between the anvil face 80 and the hammer face 85 will be fluid-tight and substantially free of liquid. Counterbore 72' is internally threaded and receives an externally threaded member 73', which bears against the packing 89.

The upper end of the hammer mandrel 81 is formed with a threaded counterbore 90'. This counterbore receives the lower end of a tubular main drive mandrel 91. The upper end of the main drive mandrel 91 is formed with a threaded pin section 92 which extends into a threaded counterbore 93 in the lower end of the central mandrel extension 37. Thus it will be seen that the central mandrel 28 has a threaded connection to the splined head 31 and that the lower end of the splined head has a threaded connection with the central mandrel extension 37. The central mandrel extension 37 is threaded to the main drive mandrel 91 and at the lower end of the main drive mandrel 91 is the hammer man-

drel 81, all of which elements when assembled produce a continuous rigid tubular structure extending centrally through the well jar. The upper end of the tubular structure is slidably mounted in the upper drive mandrel 17 which is rigidly secured to the string 10 through the coupling 13, while the lower end of the rigid tubular structure is slidably mounted in the bottom sub 76 which is rigidly secured to the fishing tool. Thus, the structure rigidly connected to the sub 13 and the structure rigidly connected to the fishing tool have relative longitudinal movement both with respect to the rigid tubular structure and with respect to each other. This movement is utilized in producing the jarring action and in creating the jarring impact between the hammer face 85 and the anvil face 80.

The present tool is designed to create jarring impact by a continuous rotation of the sub 13 and the assembled mandrel string connected therewith. The structure for producing this result is illustrated in detail in Figs. 4, 8, 10, 13, 14 and 15 of the drawings. Here it will be seen that the main drive mandrel 91 carries a top spreader bushing 94 and a lower spreader bushing 95. These bushings have a central cylindrical bore through which the main drive mandrel 91 has a sliding fit. The bushings at their outermost ends are each formed with an annular flange 96. The annular flange of the bushing 94 abuts against the end of the central mandrel extension 37 when the device is as shown in Figs. 2, 3, 4 and 5. The flange 96 of the lower spreader bushing 95 is spaced from the stop ring 73' of the anvil sub 73 in such position of the parts. Formed around the circumference of each of the bushings and disposed in opposite relation to each other is a series of circumferentially extending teeth 97 which are of the buttress type although they do not form a continuous thread. In the drawing these teeth are shown as having horizontal faces 98 and inclined back faces 99. The opposing ends of the spreader bushings 94 and 95 are spaced a distance from each other by actuating pins 100. These pins, as shown in Figs. 14 and 15 of the drawings, are disposed at 120° to each other, and as shown in Fig. 15 of the drawing the actuating pins extend longitudinally of and rest against the cylindrical face of the main drive mandrel 91. It will be seen that the spreader bushings abut against the opposite ends of the pins so that the bushings and the pins will move in unison longitudinally of the main drive mandrel. Formed upon the circumference of the main drive mandrel 91 and spaced longitudinally of the mandrel are segmental lugs 101. These lugs are indicated in Fig. 14 of the drawing where it will be seen that they have an arcuate outer face and that they are separated by grooves 102 which have parallel faces 103. The parallel faces are spaced equidistant upon opposite sides of the radial center line of the grooves. The lugs 101 are formed with cylindrical bores 104 which extend longitudinally of the lugs and parallel to the axis of the main drive mandrel 91. These bores are of a size suitable to receive the actuating pins 100 and allow them to reciprocate as the tool operates.

Mounted upon the spreader bushings and designed to embrace the bushings is a split nut structure indicated at 105. This structure fits between the annular flanges 96 on the spreader bushings 94 and 95 and is of a length shorter than the distance between the opposed faces of the flanges 96 by an amount as represented approxi-

mately by the distance between the faces 98 of the teeth 97. This will allow the split nut 105 to have longitudinal movement relative to the spreader bushings 94 and 95 as will be hereinafter described. The split nut comprises nut segments 106 indicated in Fig. 15 of the drawings. These segments are arcuate and their opposite edges lie in a plane substantially tangent to the circumference of the main drive mandrel 91. Each of the segments is formed with two portions of reduced width, as indicated in section at 107 in Fig. 14 of the drawings. The said portions are shown in elevation in Fig. 10 of the drawings. These portions fit in the grooves 102 occurring between the lugs 101. Thus, it will be seen that the split nut segments are held against longitudinal movement with relation to the main drive mandrel 91 while the spreader bushings 94 and 95 may have longitudinal movement within the nut segments. The nut segments are held yieldably in position around the spreader bushings by annular coil springs 108 which lie within grooves 109 occurring at the opposite ends of the segments.

The split nut segments are formed throughout their length with a continuous coarse thread 110. The thread is cut so that it will be in its normal position when the split nut is expanded, as will be hereinafter described. That is to say that when the split nut is expanded to its normal pitch diameter the threads on the outer surfaces thereof will be in helical continuity, even though there will be a space occurring between the contiguous edges of the nut segments, at which time the side walls 103 of the grooves 102 will guide the nut segments 106 so that they will move radially.

The drive housing 69 is formed with a central bore in which is cut the continuous helical thread 70. This thread is of the same pitch and tooth contour as the thread sections on the nut segments 106. Thus, when the nut segments are moved outwardly they will engage the thread 70.

The inner arcuate faces of the nut segments 106 are formed with annular teeth 111 which agree in sectional contour with the teeth 97 formed on the spreader bushings 94 and 95. By reference to Fig. 4 of the drawing it will be seen that these teeth are shown as meshing with each other and that the relatively square faces 98 of the teeth 97 abut against faces 98' of the teeth 111, and that furthermore, the inclined faces 99 of the teeth 97 lie against the inclined faces 99' of the teeth 111. Attention is also directed to the fact that the ends of the teeth 97 and 111 are blunt and flat longitudinally so that faces 112 of the teeth 97 may be contacted by faces 112' on the teeth 111 when the nut segments 106 are in their expanded positions, as shown in Fig. 8 of the drawing. In this position the thread 110 on the exterior of the nut segments 106 is in mesh with the thread 70 within the drive housing 69.

In operation of the present invention the coupling 13 is connected to a supporting string of pipe 10 and the bottom sub 76 is connected with certain fishing tools not shown in the drawing. The well jar is then placed in a position so that the parts connected with the string and those connected with the fishing tool are held against relative longitudinal movement by positioning the arcuate lugs 57 between the continuous shoulder 45 and the faces 46 of the arcuate segments 44, as shown in Fig. 16 of the drawing. This is done by rotating the lock head 39 in a counter-clockwise direction, as indicated by the arrow —a—

in Fig. 11 of the drawing, with the result that the arcuate lock lugs 57 will abut against the contiguous faces of the intermediate lugs 47 on the locking head 39. At this time the splines 32 on the splined head 31 will be disengaged, the rigid tubular mandrel assembly will have limited slideable motion and the drive housing 69 will be held against longitudinal movement with relation to the locking head 39 and the mandrel structure of which the upper drive mandrel 17 forms a part. It will also be noted as shown in Figs. 2, 3, 4 and 5 of the drawing that in the locked position the tubular mandrel structure is in its lower position with respect to the drive housing and its rigidly connected parts, so that the hammer is at the bottom of the space 90 and the top spreader bushing abuts against the shoulder of the central mandrel 37 so that the bushings are elevated with respect to the nut segments, and the teeth 97 of the spreader bushings 94 and 95 are in mesh with the complementary teeth 111 formed on the inner faces of the split nut segments 106. These teeth are held yieldably in this meshed position by the contractive action of the springs 108.

After the object to be jarred has been engaged by the fishing tool carried at the lower end of the sub 76 it is necessary to unlatch the jar and to place a strain on the object. This unlatching action is produced by rotation of the supporting string 10, the sub 13, and the upper drive mandrel 17. The action will also rotate the locking head 39 so that the arcuate lock lugs 57 will move circumferentially of the axis of the jar until they register with arcuate openings 44' occurring between the radial edges of the arcuate segments 44. This position is shown in Fig. 17 of the drawing. When a strain is then placed on the supporting string 10 the arcuate lock lugs 57 will remain substantially stationary and the arcuate segments 44 will pass upwardly between the lock lugs 57 to an unlatched position. As this movement takes place the splines 32 pass into the keyways 42 in the locking head 39 and thus key the upper drive mandrel 17 to the central mandrel extension 37 so that the main drive mandrel 91 may be rotated within the drive housing 69. Coincident with the upward movement of the locking head to engage the splines 32 the upper end of the drive mandrel extension 34 will strike the enlarged portion 28' of the central mandrel 28 to lift the tubular mandrel assembly. As the main drive mandrel is drawn upwardly incident to this movement the flanged end 96 of the spreader bushing 94 will encounter the end 64 of the spring retaining member 63. The spring 62 will thus resist upward movement of the spring retaining member and will tend to resist upward movement of the spreader bushing 94. At this same time the split nut structure 105 will be moved positively with the main drive mandrel 91 due to the engagement of the lugs 101 with the split nut segments. This will cause the faces 99' of the teeth 111 to ride up on the inclined faces 99 of the teeth 97 of both the spreader bushings 94 and 95. In turn the split nut segments 106 will move radially to positions where the teeth 110 will be held in threaded engagement with the teeth 70 of the drive housing 69. It should be noted that during the initial upward movement 70 of the string, coupling, upper and main drive mandrels, the bottom sub, anvil sub and drive housing remain stationary. Thus the hammer 84 will be raised in the space 90. During this time the supporting string 10 is rotating and imparts rotation through the coupling 13, the upper drive

mandrel 17 and the tubular mandrel extension 37 to the main drive mandrel 91. The pitch inclination of the teeth 70 and 110 are such as to insure that the main drive mandrel 91 will be placed under tension. Since the drive housing is relatively stationary, the continued rotation of the nut segments with the main drive mandrel will cause the tubular mandrel assembly to move downwardly by the threaded feed operation of the nut within the housing. Such movement will retract the hammer downwardly in the space 90. After predetermined downward movement the flange 96 of the lower bushing 95 will strike the stop ring 72', the adjustable setting of which above the end of the pin section 72 determines the blow, and the bushings will thus be forced upwardly in the nut segments. The nut segments 106 will ride off the end faces 112 of the teeth 111. This will allow the springs 108 to draw the lock nut segments 106 to retracted positions and the thread 110 out of engagement with the thread 70 in the lock nut housing. In view of the fact that the drive mandrel structure is under tension the hammer 84 will instantly move upwardly and its face 85 will strike the anvil face 80 with an impact blow represented by the stretch in the supporting pipe 10 plus the stretch produced by the pitch angle of the threads 70 and 110. As soon as the blow has been delivered the drive mandrel and associated parts will resume their original position and the spring 62 will tend to yieldably urge the spreader bushings 94 and 95 to a setting position again. It is obvious therefore that continuous driving rotation of the supporting string will cause a succession of impact blows to be created between the hammer and the anvil so long as the structure is rotated.

Attention is directed to the fact that the space occurring between the lower end of the lock housing 49 and the upper end of the anvil sub 73, as indicated at 115, will be filled with oil. This oil is introduced through an opening 116 closed normally by a threaded plug 117. By this arrangement the threaded parts will be lubricated at all times.

It will thus be seen that the present structure comprises a compact well jar which may be latched in a retracted position for entry into a well bore, the latching insuring that the fishing tool may be efficiently manipulated from the surface of the ground, after which the supporting string may be manipulated to unlatch the tool and to establish a driving connection between the supporting string and the main drive mandrel which carries an anvil, the said structure being operated by relative rotation of the main drive mandrel and the housing whereby a succession of jarring blows of a desired magnitude may be created while the drill string rotates continuously.

While we have shown the preferred form of our invention as now known to us, it will be understood that various changes may be made in combination, construction and arrangement of parts by those skilled in the art, without departing from the spirit of the invention as claimed.

Having thus described our invention, what we claim and desire to secure by Letters Patent is:

1. A rotary well jar comprising a tubular mandrel, means on the lower end of the tubular mandrel for connecting the same to a section of drill pipe or the like, a second mandrel disposed within the tubular mandrel and rotatable and reciprocable therein, a hammer fixed to the second mandrel, an anvil fixed to the tubular

mandrel and normally arranged contiguously with respect to said hammer, means for rotating said second mandrel, a first threaded member carried by said tubular mandrel, a second threaded member mounted on said second mandrel for outward movement for engagement with said first threaded member and adapted when rotated to thread downwardly on said first threaded member to cause separation of the hammer and anvil and stretching of the drill string and adapted to be moved inwardly to be disengaged from the first threaded member to release said second mandrel and allow contraction of the drill string and impact between the hammer and anvil, and means responsive to longitudinal movement of the second mandrel including a cam for causing periodic outward and subsequent inward movement of the second threaded member to cause corresponding periodic impact between the hammer and the anvil.

2. A rotary well jar comprising a tubular mandrel, means on the lower end of the tubular mandrel for connecting the same to a section of drill pipe or the like, a second mandrel disposed within the tubular mandrel and rotatable and reciprocable therein and adapted to be connected to a drill string, a hammer fixed to the second mandrel, an anvil fixed to the tubular mandrel and normally arranged contiguously with respect to said hammer, means for rotating said second mandrel, a first threaded member carried by said tubular mandrel, a second threaded member mounted on said second mandrel for outward movement for engagement with said first threaded member and adapted when rotated to thread downwardly on said first threaded member to cause separation of the hammer and anvil, and stretching of the drill string and adapted to be moved inwardly to be disengaged from the first threaded member to release said second mandrel and allow contraction of the drill string and impact between the hammer and anvil, means responsive to longitudinal movement of the second mandrel and including a cam for causing periodic outward and subsequent inward movement of the second threaded member to cause periodic impact between the hammer and anvil, means carried by the tubular mandrel for moving the cam to camming position, and means carried by the tubular mandrel and spaced from the last named means for moving the cam to inoperative position.

3. A rotary well jar comprising a tubular mandrel, means on the lower end of the tubular mandrel for connecting the same to a section of drill pipe or the like, a second mandrel disposed within the tubular mandrel and rotatable and reciprocable therein and adapted to be connected to a drill string, a hammer fixed to the second mandrel, an anvil fixed to the tubular mandrel and normally arranged contiguously with respect to said hammer, means for rotating said second mandrel, a first threaded member carried by said tubular mandrel, a second threaded member mounted on said second mandrel for outward movement for engagement with said first threaded member and adapted when rotated to thread downwardly on said first threaded member to cause separation of the hammer and anvil, and stretching of the drill string and adapted to be moved inwardly to be disengaged from the first threaded member to release said second mandrel and allow contraction of the drill string and impact between the hammer and anvil, means including a cam for causing periodic out-

ward and subsequent inward movement of the second threaded member to cause periodic impact between the hammer and anvil, said cam being mounted on said second mandrel for limited longitudinal sliding movement relative thereto in one direction to cam the second threaded member outwardly and limited longitudinal movement in the opposite direction to allow inward movement of the second threaded member, means for urging inward movement of the second threaded member, means carried by the tubular mandrel for moving the cam to camming position, and means carried by the tubular mandrel and spaced from the last named means for moving the cam to inoperative position.

4. A rotary well jar comprising a tubular mandrel, means on the lower end of the tubular mandrel for connecting the same to a section of drill pipe or the like, a second mandrel disposed within the tubular mandrel and rotatable and reciprocable therein and adapted to be connected to a drill string, a hammer fixed to the second mandrel, an anvil fixed to the tubular mandrel and normally arranged contiguously with respect to said hammer, means for rotating said second mandrel, a first threaded member carried by said tubular mandrel, a second threaded member mounted on said second mandrel for outward movement for engagement with said first threaded member and adapted when rotated to thread downwardly on said first threaded member to cause separation of the hammer and anvil, and stretching of the drill string and adapted to be moved inwardly to be disengaged from the first threaded member to release said second mandrel and allow contraction of the drill string and impact between the hammer and anvil, means including a cam for causing periodic outward and subsequent inward movement of the second threaded member to cause periodic impact between the hammer and anvil, said cam being mounted on said second mandrel for limited longitudinal sliding movement relative thereto in one direction to cam the second threaded member outwardly and limited longitudinal movement in the opposite direction to allow inward movement of the second threaded member, means for urging inward movement of the second threaded member, means carried by the tubular mandrel for moving the cam to camming position, means carried by the tubular mandrel and spaced from the last named means for moving the cam to inoperative position, means attachable to a drill string and connected to said second mandrel for moving said second mandrel to a position to cause an initial engagement of said last named means and said cam to cause an initial engagement between the threaded members.

5. A rotary well jar comprising a tubular mandrel, means on the lower end of the tubular mandrel for connecting the same to a section of drill pipe or the like, a second mandrel disposed within the tubular mandrel and rotatable and reciprocable therein and adapted to be connected to a drill string, a hammer fixed to the second mandrel, an anvil fixed to the tubular mandrel and normally arranged contiguously with respect to said hammer, means for rotating said second mandrel, a first threaded member carried by said tubular mandrel, a second threaded member mounted on said second mandrel for outward movement for engagement with said first threaded member and adapted when rotated to thread downwardly on said first threaded member.

ber to cause separation of the hammer and anvil, and stretching of the drill string and adapted to be moved inwardly to be disengaged from the first threaded member to release said second mandrel and allow contraction of the drill string and impact between the hammer and anvil, means including a cam for causing periodic outward and subsequent inward movement of the second threaded member to cause periodic impact between the hammer and anvil, said cam being mounted on said second mandrel for limited longitudinal sliding movement relative thereto in one direction to cam the second threaded member outwardly and limited longitudinal movement in the opposite direction to allow inward movement of the second threaded member, means for urging inward movement of the second threaded member, means carried by the tubular mandrel for moving the cam to camming position, means carried by the tubular mandrel and spaced from the last named means for moving the cam to inoperative position, means attachable to a drill string and connected to said second mandrel for moving said second mandrel to a position to cause an initial engagement of said last named means and said cam to cause an initial engagement between the threaded members and having a driving connection with said second mandrel for rotating the same.

6. A rotary well jar comprising a tubular mandrel, means on the lower end of the tubular mandrel for connecting the same to a section of drill pipe or the like, a second mandrel disposed within the tubular mandrel and rotatable and reciprocable therein and adapted to be connected to a drill string, a hammer fixed to the second mandrel, an anvil fixed to the tubular mandrel and normally arranged contiguously with respect to said hammer, means for rotating said second mandrel, a first threaded member carried by said tubular mandrel, a second threaded member mounted on said second mandrel for outward movement for engagement with said first threaded member and adapted when rotated to thread downwardly on said first threaded member to cause separation of the hammer and anvil, and stretching of the drill string and adapted to be moved inwardly to be disengaged from the first threaded member to release said second mandrel and allow contraction of the drill string and impact between the hammer and anvil, means including a cam for causing periodic outward and subsequent inward movement of the second threaded member to cause periodic impact between the hammer and anvil, said cam being mounted on said second mandrel for limited longitudinal sliding movement relative thereto in one direction to cam the second threaded member outwardly and limited longitudinal movement in the opposite direction to allow inward movement of the second threaded member, means for urging inward movement of the second threaded member, means carried by the tubular mandrel for moving the cam to camming position, means carried by the tubular mandrel and spaced from the last named means for moving the cam to inoperative position, means attachable to a drill string and connected to said second mandrel for moving said second mandrel to a position to cause an initial engagement of said last named means and said cam to cause an initial engagement between the threaded members and having a driving connection with said second mandrel for rotating the same.

same and having a disconnectible driving connection with said tubular mandrel.

7. A rotary well jar comprising a tubular mandrel, means on the lower end of the tubular mandrel for connecting the same to a section of drill pipe or the like, a second mandrel disposed within the tubular mandrel and rotatable and reciprocable therein and adapted to be connected to a drill string, a hammer fixed to the second mandrel, an anvil fixed to the tubular mandrel and normally arranged contiguously with respect to said hammer, means for rotating said second mandrel, a first threaded member carried by said tubular mandrel, a second threaded member mounted on said second mandrel for outward movement for engagement with said first threaded member and adapted when rotated to thread downwardly on said first threaded member to cause separation of the hammer and anvil, and stretching of the drill string and adapted to be moved inwardly to be disengaged from the first threaded member to release said second mandrel and allow contraction of the drill string and impact between the hammer and anvil, means including a cam for causing periodic outward and subsequent inward movement of the second threaded member to cause periodic impact between the hammer and anvil, said cam being mounted on said second mandrel for limited longitudinal sliding movement relative thereto in one direction to cam the second threaded member outwardly and limited longitudinal movement in the opposite direction to allow inward movement of the second threaded member, means for urging inward movement of the second threaded member, means carried by the tubular mandrel for moving the cam to camming position, and means carried by the tubular mandrel and spaced from the last named means for moving the cam to inoperative position, means attachable to a drill string and telescopically engaging both said mandrels and movable relative to the mandrels to one position to drivingly engage one mandrel and to another position to drivingly engage the other mandrel.

8. A rotary well jar comprising a tubular mandrel, means on the lower end of the tubular mandrel for connecting the same to a section of drill pipe or the like, a second mandrel disposed within the tubular mandrel and rotatable and reciprocable therein and adapted to be connected to a drill string, a hammer fixed to the second mandrel, an anvil fixed to the tubular mandrel and normally arranged contiguously with respect to said hammer, means for rotating said second mandrel, a first threaded member carried by said tubular mandrel, a second threaded member mounted on said second mandrel for outward movement for engagement with said first threaded member and adapted when rotated to thread downwardly on said first threaded member to cause separation of the hammer and anvil, and stretching of the drill string and adapted to be moved inwardly to be disengaged from the first threaded member to release said second mandrel and allow contraction of the drill string and impact between the hammer and anvil, means including a cam for causing periodic outward and subsequent inward movement of the second threaded member to cause periodic impact between the hammer and anvil, said cam being mounted on said second mandrel for limited longitudinal sliding movement relative thereto in one direction to cam the second threaded member outwardly and limited longitudinal move-

ment in the opposite direction to allow inward movement of the second threaded member, means for urging inward movement of the second threaded member, means carried by the tubular mandrel for moving the cam to camming position, means carried by the tubular mandrel and spaced from the last named means for moving the cam to inoperative position, means attachable to a drill string and telescopically engaging both said mandrels and movable relative to the mandrels to one position to drivingly engage one mandrel and to another position to drivingly engage the other mandrel, and connected to said second mandrel for moving said second mandrel to a position to cause an initial engagement of said last named means with said cam to cause an initial engagement between the threaded members.

9. A rotary well jar comprising a tubular mandrel, means on the lower end of the tubular mandrel for connecting the same to a section of drill pipe or the like, a second mandrel disposed within the tubular mandrel and rotatable and reciprocable therein and adapted to be connected to a drill string, a hammer fixed to the second mandrel, an anvil fixed to the tubular mandrel and normally arranged contiguously with respect to said hammer, means for rotating said second mandrel, a first threaded member carried by said tubular mandrel, a second threaded member mounted on said second mandrel for outward movement for engagement with said first threaded member and adapted when rotated to thread downwardly on said first threaded member to cause separation of the hammer and anvil, and stretching of the drill string and adapted to be moved inwardly to be disengaged from the first threaded member to release said second mandrel and allow contraction of the drill string and impact between the hammer and anvil, means including a cam for causing periodic outward and subsequent inward movement of the second threaded member to cause periodic impact between the hammer and anvil, said cam being mounted on said second mandrel for limited longitudinal sliding movement relative thereto in one direction to cam the second threaded member outwardly and limited longitudinal movement in the opposite direction to allow inward movement of the second threaded member, means for urging inward movement of the second threaded member, means carried by the tubular mandrel for moving the cam to camming position, means carried by the tubular mandrel and spaced from the last named means for moving the cam to inoperative position, means attachable to a drill string and telescopically engaging both said mandrels and movable relative to the mandrel to one position to drivingly engage one mandrel and to another position to drivingly engage the other mandrel and having limited upward movement with respect to said second mandrel to enable lifting of the second mandrel to cause an initial engagement of the cam and said last named means and thereby an initial engagement between said threaded members.

10. A rotary well jar comprising a tubular mandrel, means on the lower end of the tubular mandrel for connecting the same to a section of drill pipe or the like, a second mandrel disposed within the tubular mandrel and rotatable and reciprocable therein and adapted to be connected to a drill string, a hammer fixed to the second mandrel, an anvil fixed to the tubular

mandrel and normally arranged contiguously with respect to said hammer, means for rotating said second mandrel, a first threaded member carried by said tubular mandrel, a second threaded member mounted on said second mandrel for outward movement for engagement with said first threaded member and adapted when rotated to thread downwardly on said first threaded member to cause separation of the hammer and anvil, and stretching of the drill string and adapted to be moved inwardly to be disengaged from the first threaded member to release said second mandrel and allow contraction of the drill string and impact between the hammer and anvil, means including a cam for causing periodic outward and subsequent inward movement of the second threaded member to cause periodic impact between the hammer and anvil, said cam being mounted on said second mandrel for limited longitudinal sliding movement relative thereto in one direction to cam the second threaded member outwardly and limited longitudinal movement in the opposite direction to allow inward movement of the second threaded member, means for urging inward movement of the second threaded member, means carried by the tubular mandrel for moving the cam to camming position, means carried by the tubular mandrel and spaced from the last named means for moving the cam to inoperative position, means attachable to a drill string and telescopically engaging both said mandrels and movable upwardly relative to the mandrels to establish a driving connection to said second mandrel and movable downwardly relative to said mandrel to establish a driving connection with said tubular mandrel and having limited upward movement relative to said second mandrel to enable lifting of the second mandrel to cause an initial engagement of the cam and said last named means and thereby an initial engagement of said threaded members.

11. A rotary well jar, comprising first and second mandrels coaxially arranged for relative rotary and axial movement and adapted to be connected to a supporting drill string and a member to be jarred respectively, a hammer and an anvil fixed one to each of the mandrels and being contiguously disposed in axial registry with respect to one another, means responsive to rotation of the first mandrel relative to the second mandrel for causing downward movement of the first mandrel relative to the second mandrel to stretch the drill string and separate the hammer and anvil, said means comprising a continuous thread formed on one mandrel and a mating threaded member engaging said continuous thread and being mounted on said other mandrel for radial separating movement for disengagement from the continuous thread on said one mandrel to allow the drill string to contract to cause a violent impact between the hammer and anvil, and means responsive to a predetermined amount of downward movement of the first mandrel relative to the second mandrel to cause a separation of the threaded connection between the mandrels and being operable upon a return of the first mandrel to its upward position to cause a re-engagement of the threaded member with the continuous thread, whereby a series of violent jars will be produced upon continuous rotation of the first mandrel relative to the second mandrel.

12. A rotary well jar, comprising first and second mandrels coaxially arranged for relative

rotary and axial movement and adapted to be connected to a supporting drill string and a member to be jarred respectively, a hammer and an anvil fixed one to each of the mandrels and being contiguously disposed in axial registry with respect to one another, means responsive to rotation of the first mandrel relative to the second mandrel for causing downward movement of the first mandrel relative to the second mandrel to stretch the drill string and separate the hammer and anvil, said means comprising a thread formed on one mandrel and a mating threaded member engaging said thread and being mounted on said other mandrel for radial separating movement for disengagement from said thread to allow the drill string to contract and cause a violent impact between the hammer and anvil, and means responsive to a predetermined amount of downward movement of the first mandrel relative to the second mandrel to cause a radial separation of the threaded connection between the mandrel and being operable upon a return of the first mandrel to its upward position to cause a re-engagement of the threaded member with said thread, whereby a series of violent jars can be obtained upon continuous rotation of the first mandrel relative to the second mandrel.

13. A rotary well jar, comprising first and second mandrels coaxially arranged for relative rotary and axial movement and adapted to be connected to a supporting drill string and a member to be jarred respectively, a hammer and an anvil fixed one to each of the mandrels and being contiguously disposed in axial registry with respect to one another, means responsive to rotation of the first mandrel relative to the second mandrel for causing downward movement of the first mandrel relative to the second mandrel to stretch the drill string and separate the hammer and anvil, said means comprising a continuous thread formed on one mandrel and a mating threaded member engaging said continuous thread and being mounted on said other mandrel for radial separating movement for disengagement from the continuous thread on said one mandrel to allow the drill string to contract to cause a violent impact between the hammer and anvil, and means responsive to a predetermined amount of downward movement of the first mandrel relative to the second mandrel to cause a separation of the threaded connection between the mandrels and being operable upon a return of the first mandrel to its upward position to cause a re-engagement of the threaded member with the continuous thread, whereby a series of violent jars will be produced upon continuous rotation of the first mandrel relative to the second mandrel, the last-named means including spring means urging radial disengagement of the threaded member from said continuous thread.

14. A rotary well jar, comprising first and second mandrels coaxially arranged for relative rotary and axial movement and adapted to be connected to a supporting drill string and a member to be jarred respectively, a hammer and an anvil fixed one to each of the mandrels and being contiguously disposed in axial registry with respect to one another, means responsive to rotation of the first mandrel relative to the second mandrel for causing downward movement of the first mandrel relative to the second mandrel to stretch the drill string and separate the hammer and anvil, said means comprising a thread formed on one mandrel and a mating threaded member engaging said thread and being mounted on said

other mandrel for radial separating movement for disengagement from said thread to allow the drill string to contract and cause a violent impact between the hammer and anvil, and means responsive to a predetermined amount of downward movement of the first mandrel relative to the second mandrel to cause a radial separation of the threaded connection between the mandrels and being operable upon a return of the first mandrel to its upward position to cause a re-engagement of the threaded member with said thread, whereby a series of violent jars can be obtained upon continuous rotation of the first mandrel relative to the second mandrel, the last-named means including spring means urging disengagement of the threaded member from said thread and cam means for causing re-engagement of the threaded member with said thread.

15. A rotary well jar, comprising first and second mandrels coaxially arranged for relative rotary and axial movement and adapted to be connected to a supporting drill string and a member to be jarred respectively, a hammer and an anvil fixed one to each of the mandrels and being contiguously disposed in axial registry with respect to one another, means responsive to rotation of the first mandrel relative to the second mandrel for causing downward movement of the first mandrel relative to the second mandrel to stretch the drill string and separate the hammer and anvil, said means comprising a continuous thread formed on one mandrel and a mating threaded member engaging said continuous thread and being mounted on said other mandrel for radial separating movement for disengagement from the continuous thread on said one mandrel to allow the drill string to contract to cause a violent impact between the hammer and anvil, and means responsive to a predetermined amount of downward movement of the first mandrel relative to the second mandrel to cause a separation of the threaded connection between the mandrels and being operable upon a return of the first mandrel to its upward position to cause a re-engagement of the threaded member with the continuous thread, whereby a series of violent jars will be produced upon continuous rotation of the first mandrel relative to the second mandrel, the last-named means including cam means carried by said other mandrel engageable with an abutment device on said one mandrel to cause engagement of the threaded member and said continuous thread.

16. A rotary well jar, comprising first and second mandrels coaxially arranged for relative rotary and axial movement and adapted to be connected to a supporting drill string and a member to be jarred respectively, a hammer and an anvil fixed one to each of the mandrels and being contiguously disposed in axial registry with respect to one another, means responsive to rotation of the first mandrel relative to the second mandrel for causing downward movement of the first mandrel relative to the second mandrel to stretch the drill string and separate the hammer and anvil, said means comprising a continuous thread formed on one mandrel and a mating threaded member engaging said continuous thread and being mounted on said other mandrel for radial separating movement for disengagement from the continuous thread on said one mandrel to allow the drill string to contract to cause a violent impact between the hammer and anvil, and means responsive to a predetermined

amount of downward movement of the first mandrel relative to the second mandrel to cause a separation of the threaded connection between the mandrels and being operable upon a return of the first mandrel to its upward position to cause a re-engagement of the threaded member with the continuous thread, whereby a series of violent jars will be produced upon continuous rotation of the first mandrel relative to the second mandrel, the last-named means including spring means urging the threaded member out of engagement with said thread and cam means carried by said other mandrel engageable with an abutment device on said one mandrel to cause engagement of the threaded member and said thread, and subsequently with an axially displaced abutment on said one mandrel to release the threaded member for disengagement from the said thread under the influence of the spring means.

20 17. A rotary well jar, comprising first and second mandrels coaxially arranged for relative rotary and axial movement and adapted to be connected to a supporting drill string and a member to be jarred respectively, a hammer and an anvil fixed one to each of the mandrels and being contiguously disposed in axial registry with respect to one another, means responsive to rotation of the first mandrel relative to the second mandrel for causing downward movement of the first mandrel relative to the second mandrel to stretch the drill string and separate the hammer and anvil, said means comprising a thread formed on one mandrel and a mating threaded member engaging said thread and being mounted on said other mandrel for radial separating movement for disengagement from said thread to allow the drill string to contract and cause a violent impact between the hammer and anvil, and means responsive to a predetermined amount of downward movement of the first mandrel relative to the second mandrel to cause a radial separation of the threaded connection between the mandrel and being operable upon a return of the first mandrel to its upward position to cause a re-engagement of the threaded member with said thread, whereby a series of violent jars can be obtained upon continuous rotation of the first mandrel relative to the second mandrel, the last-named means including spring means urging the threaded member out of engagement with said thread and cam means carried by said other mandrel engageable with an abutment device on said one mandrel to cause engagement of the threaded member and said thread, and subsequently with an axially displaced abutment on said one mandrel to release the threaded member for disengagement from the said thread under the influence of the spring means.
